UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

LAST.

1,242,145.

Specification of Letters Patent.

Patented Oct. 9, 1917.

Application filed March 26, 1917. Serial No. 157,392.

To all whom it may concern:

Be it known that I, GEORGE CLAUSING, a citizen of the United States, residing in the city of Portsmouth, in the county of Scioto and State of Ohio, have invented certain new and useful Improvements in Lasts, Case J, of which the following is a specification.

One of the objects of the invention is to produce a simple, strong and practical last which can be broken or flexed so as to facilitate the ready removal of the last from the shoe and so that the shoe, during the removal of the last, will not be marred or broken or pulled out of shape.

According to the present invention, a last is constructed so that it will comprise a toe part and a heel part having provided between them main bearing pins or members that extend horizontally and transversely to the last. The toe and heel parts preferably bear directly against said pins and are maintained in proper position relative to said pins by a connecting link that is connected at one end to the toe part of the last and at the other end to the heel part of the last by small pivot pins or rivets that pass through said link.

The last is also provided with a spring means or locking mechanism which engages an end portion of said link. This spring or locking mechanism just referred to is preferably mounted in and carried by the toe portion of the last and is arranged so as to engage the under side of a projecting free end portion at the forward end of said link, whereby the pressure exerted by the spring will tend to constantly force the link to the position which the link occupies when the last parts are in extended position.

As showing a specific embodiment of the invention, reference is made to the drawing forming part of this specification, in which—

Figure 1 shows a vertical sectional view taken as on the plane indicated by the line 1—1 of Fig. 2. In said Fig. 1 the parts are shown in their extended or unbroken position.

Fig. 2 is a sectional view taken as on the plane indicated by the line 2—2 of Fig. 1 and is a view looking in the direction of the arrows.

Fig. 3 is a view taken as on the plane 3—3 of Fig. 1 looking in the direction of the arrows.

The last is designated by the reference

character A and comprises the forward or toe part B and the rear or heel part C. In the formation of these lasts these two parts are preferably made integral with each other from the same piece of wood and they are separated as by sawing.

From an inspection of Fig. 1 it will be observed that a V-shaped portion has been cut out or removed from the upper portion of the last, whereby the heel part and the toe part can be moved relative to each other and on the main bearing pins or members D that are provided between said last parts.

The longitudinally extending link E is pivotally connected at the rear end thereof to the heel part C by means of the rivet or pin F and at the forward portion or end to the toe part B by means of the rivet or pin G. The rivets F and G are frequently referred to as a set of rivets. This link is 75 preferably arranged so that when the last parts are in their extended position the line passing through the center of said rivets F and G is located below the center line of the main bearing pins D. When, however, the 80 last parts are moved to their unbroken position, the line that passes through the center of the rivets G and F assumes a position above the center line of the main bearing pins B.

This construction is preferably the same as that shown and described in United States Letters Patent No. 1,085,668, which was granted on February 3, 1914, for improvements in lasts invented by myself.

In the present construction the forward end or forward end portion of the link is extended as at H somewhat beyond the rivet in the toe part, namely rivet G of the sets of rivets F and G. This allows a free or 95 movable portion at the forward end of the link and this free forward portion is cut out on its under side in order to provide a seat L against which a spring locking or spring holding mechanism M presses. This spring locking mechanism comprises a compression spring N and the cap, ball or head O and this cap, ball or head is the portion which directly engages the seat on the extending portion H of the connecting link. The lower 100 end of the spring is seated in a cavitated portion in the forward or toe part of the last and it will be observed that the center line of pressure, Q—Q, of this spring locking means is located ahead of the rivet or pin G; 110

in other words is located outside of the set of rivets, that is, is located beyond the rivets and not at one of the rivets nor between the rivets. As this spring continuously presses upwardly, against the movable, extending or projecting forward end of said link, it consequently tends to force downwardly the portion of the link between the rivet pins G and E, whereby the last parts will tend to 5 assume their extended position, if not in that position, and also whereby the link tends to maintain said last parts in extended position when in said position.

The connecting link shown is preferably 15 formed of a round piece of material which has been flattened at opposite sides at e', as will be noted from an inspection of Fig. 3, and a receiving space for said link is provided in the toe and heel parts as by boring 20 holes or in any other suitable manner. In order that the last parts may be flexed or moved to broken position, a portion at the top has been cut out or removed, as at XYZ.

The main bearing pins D are each provided 25 on their adjacent inner end with the head or enlarged portion d' and in the construction shown on the drawings it is not necessary to directly secure the main bearing pins or members D to the toe or heel 30 part, since according to the construction illustrated on the drawings in the present application, the connecting link Y holds the heel and toe parts together so that a receiving socket will be provided between them 35 for the main bearing pins, and manifestly the said pins when in place will not move outwardly from their operative position between said parts because they are prevented from doing so by said enlarged heads or 40 flange portions d'. The inward movement of said bearing pins is limited by their inner ends engaging the side portions of the connecting link.

The improvements herein set forth are not 45 limited to the precise construction and arrangement shown and described and may be embodied in various forms and modifications without departing from the spirit and scope of the invention.

50 What I claim is:

1. A last having a toe part, a heel part 55 movable relative thereto, main bearing pins or members between said heel and toe parts, a link pivotally connected at one end to said heel part by a pin or rivet and at the other end to said toe part by a pin or rivet, which link has an end portion that lies beyond the rivets, and a spring holding means 60 which engages said end portion in a manner to hold the last parts in extended or unbroken position when in said position.

2. A last having a toe part, a heel part 65 movable relative thereto, horizontally and transversely extending main bearing pins

or members between and engaging or engaged by said parts, a longitudinally extending link connected at one end to the heel part by a pin or rivet and at the other end to the toe part by a pin or rivet, said link having a projecting end located beyond the 70 set of rivets, and spring means pressing upwardly against said projecting end so as to hold the heel and toe parts in extended or unbroken position when in said position, said last being provided at its upper portion 75 with a cutaway portion whereby the toe part can be swung to flexed or broken position relative to the heel part.

3. A last having a toe part, a heel part 80 movable relative to the toe part, the movement of which heel part takes place on main bearing pins or members that are on or engage the toe part, a link connected at one end to the heel part by a pin or rivet and at the other end to the toe part by a pin or 85 rivet, said link having an end portion that extends beyond the rivets which constitute a set of rivets, the line passing through the center of said rivets being located below the 90 center line of the main bearing pins or members when the heel and toe parts are in extended position, and a spring holding means which presses upwardly against said extending end portion.

4. A last having a toe part, a heel part 95 movable relative thereto and upon main bearing pins common to said parts, a link pivotally connected at one end to the heel part and at the other end to the toe part, which link has a forwardly projecting or extending end portion, and a compression 100 spring seated in the toe part, which spring extends upwardly and rearwardly so as to press against said forwardly projecting or extending end portion.

5. A last having a toe part, a heel part, a link pivotally connected to the toe part, which link is also pivotally connected to the heel part, said link also having an end portion 110 that lies beyond the set of rivets connecting the link to the toe and heel parts, and a spring means comprising a compression spring and ball, the latter of which engages the under side of said forwardly extending end portion of said link, one end of said 115 spring engaging the ball and the other end of said spring being seated in the bottom of a cavity that is provided within the toe part.

6. A last having a toe part, a heel part, a link connected to the toe part by a pin or 120 rivet, and to the heel part by a pin or rivet, said link having a forwardly extending end portion that is located beyond the set of rivets, and a compression spring which exerts an upward pressure against said forward end portion, said spring being seated 125 within a cavity within the toe part, and the center line of the pressure exerted by said

spring being located ahead of the center of the rivet or pin that connects the link to the toe part.

7. A last having a toe part, a heel part, a link connecting said parts, and main bearing pins between said parts, said bearing pins being provided with flanges or collars that retain said pins in place. 15

8. A last having a toe part, a heel part, a connecting link between said parts, and flanged bearing pins which are received in sockets provided by and between said last parts. 20

9. A last having a toe part, a heel part,

means for connecting said parts, and bearing pins between said parts, which bearing pins are provided at their adjacent inner ends with flanges that are arranged so as to retain said pins from being moved from their operative position when said last parts are connected by said means.

This specification signed and witnessed this 20th day of March, A. D., 1917.

GEORGE CLAUSING.
